UNITED STATES PATENT OFFICE.

JOHN FRANK WEST, OF STAUNTON, VIRGINIA.

CABLE-GRIP.

SPECIFICATION forming part of Letters Patent No. 377,702, dated February 7, 1888.

Application filed June 15, 1887. Serial No. 241,408. (No model.)

To all whom it may concern:

Be it known that I, JOHN FRANK WEST, of Staunton, in the county of Augusta and State of Virginia, have invented a new and useful 5 Improvement in Cable-Grips, of which the following is a specification.

My invention relates to improvements in cable-railway grips.

The object of my invention is to provide a 10 simple device for operating the movable jaws, both to grip the operating-cable and to lift them, together with the grip head, a sufficient distance above the line of the operating-cable to pass cross-cables or sheave-rollers of other 15 lines located above said operating-cable; and the improvement consists in the peculiar construction and arrangement of parts hereinafter particularly described, and pointed out in the claims.

20 In the accompanying drawings, Figure 1 is a side elevation with the floor of the car in section, showing the preferred form of my invention; Fig. 2, an enlarged cross-section in line $x-x$ of Fig. 1, showing the hand-lever and 25 its connections in elevation; Fig. 3, an enlarged end elevation, partly in section, of the gripping-jaws; Fig. 4, an enlarged side elevation, partly in section, showing a modification of the gripping-jaws. Fig. 5 is a front elevation 30 showing a modification of the mechanism for raising and lowering the sliding head.

The floor or framing of the car A supports a hanger bar, B, bolted thereto, which passes through the opening in the cable-tube. The 35 lower end of the hanger-bar B is enlarged at b to hold the gripping-jaws in their lower position to grasp the cable D, and brace-rods B' B² pass through the opening in the cable-tube and connect the front and rear edge of 40 the hanger-bar B with the framing of the car. The bar B terminates a sufficient distance above the cable D to clear any cross-cables D', which may be in the way of the gripping device.

45 The gripping-jaws C C' are hinged at C² to a sleeve, C³, which snugly fits and slides upon the hanger-bar B, as shown in Figs. 1 and 3. The upper ends of the jaws C C' fit in recesses upon the sides of the sleeve C³, and springs C⁴ pass between the side of the sleeve C³ and the opposing side of the jaws C C', to hold said jaws, when not otherwise acted upon, a suffi-

cient distance apart to clear the operating-cable when they are raised upon the hanger-bar B. The lower ends of the jaws C C' are 55 curved to fit the cable and are spread laterally to secure increased bearing-surface.

The jaws C C' are bowed outwardly at their lower ends, and a sliding head, E, fitted upon the hanger-bar B, and having a yoke, E', at its 60 lower end to embrace the jaws C C' and force them together at the lower end of the movement of the said yoke E'. The head E has a sleeve, E², at its upper end, and a sleeve, E³, connected with the sleeve E² by side plates, E⁵, 65 to fit snugly upon the hanger-bar B. The yoke E', at the lower end of the head E, with its cross-bars E⁴ upon the forward and rear sides of the bar B, is connected by side plates, E⁶, with the sleeve E². The cross-bars E⁴ fit upon the 70 bar B, beneath the sleeve C³ of the gripping-jaws, and when the head E has been raised a sufficient distance for the yoke E' to release the gripping-jaws from the cable the said cross-bars E⁴ will press beneath the sleeve C³ 75 and raise the jaws C C' above the cable until their lower ends are opposite the lower end of the hanger-bar B, a sufficient distance above the cable D to clear a cross-cable, D', which may be in the way or path of movement of the 80 gripping device.

It will thus appear that the gripping-jaws C C' and the sliding head E are both raised together (after the cable has been released by the jaws) above the cable a sufficient distance 85 to be out of the way, a single lifting or operating device serving to effect the triple purpose of gripping, releasing, and lifting the gripping mechanism above the cable to be out of the way.

90 The jaws C C' are preferably provided with a tongue, C⁶, running longitudinally upon the outer face thereof, and the yoke E' is correspondingly grooved at e to fit the said tongues, and together therewith brace and hold the 95 jaws and the lower end of the sliding head firmly together.

Pins e' (shown by detail in Fig. 4) project inwardly from the bars E⁴ upon both ends thereof and upon both sides of the jaws C C' and engage with inclined grooves C⁶ in the edges of the jaws C C', and serve to open and close said jaws by positive mechanism, when the yoke is raised and lowered upon the jaws, in

lieu of the springs shown in Fig. 3 of the drawings.

The sliding head E is raised and lowered by a pitman, F, connected by a wrist-pin, f, at 5 one end to the sleeve E' of the said head, and at the other end by a wrist-pin, g, with a flanged band-wheel, G, keyed to a shaft, G', supported in bearings upon the frame of the car. A metal chain belt, H, formed of open 10 links to receive pins g' and fit closely upon the periphery of the wheel G, passes over said wheel and over a correspondingly-flanged band-wheel, I, having pins i and keyed to a shaft, I', supported in bearings upon the frame of 15 the car. Gear-pinions I' upon the shaft I', upon opposite sides of the band-wheel I, gear with toothed segment-racks K K, supported upon a shaft, K', and having a hand-lever, K², cast integral therewith, by which means the power 20 from the lever K² may be applied evenly upon both ends of the shaft I. A notched segment-rack, L, secured to the frame of the car, and a spring locking-bolt, l, of well-known construction, are supported upon the lever K² to 25 lock the lever at the end of its movement in either direction.

The mechanism above described for raising and lowering the sliding head E may be varied without departing from my invention. One 30 modification of the mechanism for this purpose is shown in Fig. 5, wherein the sliding head E has a toothed rack, F^x, upon one of its edges, into which a toothed wheel, G^x, is geared to raise and lower the sliding head. The wheel 35 G^x is secured to the shaft G', which is rotated by any well-known or preferred mechanical device. The bar B and the pitman F may be lengthened or shortened to suit roads and cars of varying dimensions.

40 In operation, when it is desired to grip the operating-cable, the head E is lowered upon the bar B until the sleeve C³ of the jaws C C' is arrested by and supported upon the projections b upon the lower end of said bar B, and 45 the gripping ends of the jaws C C' are held upon opposite sides of the cable D. The head E is now lowered a further distance upon the bar B, and the yoke E' of the head E will press upon the bulged portions of the jaws C C' at 50 the gripping ends thereof to firmly clamp them upon the cable. When thus clamped, the latch l of the lever K² will engage with the notch at one end of the segment-rack and hold the jaws in their working position. When 55 it is desired to release the cable, the lever K² is unlocked and the head E is raised by pushing forward the lever to the notch at the opposite end of the segment-rack, to engage therewith and hold the head E positively in 60 its raised position. The yoke E' of the head E, at the beginning of its upward movement, releases the jaws C C', and by a continuation of the upward movement of said head the cross-bars E' press beneath the sleeve C³ and raise 65 it, together with the jaws C C', until the lower ends of said jaws are opposite the lower end

of the bar B, and are, together with the head E, placed and held completely out of the way. It will thus be seen that when the head E is raised to its highest position the gripping device will pass over any obstruction beneath the level of the head b upon the lower end of the bar B.

It is only necessary to move the lever K² a short distance to open the jaws and release the 75 cable without elevating said jaws, which is therefore done almost instantaneously, and the car may thus be stopped and started without loss of time and without friction or slippage of the jaws upon the cable. The jaws C C' 80 extend but slightly below the horizontal diameter of the cable, and will thus pass over the sheaves or rollers which support the cable without interfering with them and without detaching and raising the grip to pass the said 85 rollers.

The lever K², provided with segment-racks K K, will act equally upon both ends of the shaft I', and permit the band-wheel I upon said shaft to come directly beneath the hand-lever and between the segment-racks, thus 90 enabling the power to be applied directly and effectively.

The jaws C C' may be extended a sufficient 95 distance in the line of the cable to give ample surface contact or bearing upon the cable, and the inner faces of said jaws may be filled with anti-friction metal which may be renewed from time to time as it wears away.

The mechanism being operated by one movement of the lever and securely locked in either position, provides a safe, instantaneous, and effective device, by means of which the car 100 may be quickly stopped or started.

I claim as my invention and desire to secure 105 by Letters Patent—

1. The combination, in a cable-grip, the hanger-bar supported upon the car and terminating a sufficient distance above the level, of cables or cross-cables located beneath the surface to 110 clear them, hinged jaws adapted to slide upon the hanger-bar, and a sliding head supported to slide independently upon said bar, the sliding head serving to thus raise, lower, open, and close the hinged jaws, substantially as and 115 for the purpose described.

2. In a cable-grip, the combination, with the hanger-bar, of hinged jaws and a sliding head, all supported to move independently upon said bar to project below the same when gripping 120 the cable, and to be raised together out of the way of cross-cables by the upward movement of the sliding head, substantially as described.

3. In a cable-grip, the combination, with the hanger-bar, of the sliding head and hinged 125 jaws, all adapted to slide upon said bar independently of the head, to be raised by the head and fall of their own gravity, and a yoke upon the lower end of the sliding head to force the jaws together, substantially as described.

4. The combination, in a cable-grip, of the hanger-bar B, with the sliding head E, the 130

jaws C C', sliding upon the said bar independently of the head E, a yoke, E', upon the sliding head to embrace the jaws beneath the sleeve to which the jaws are attached, and 5 means for raising both the jaws and head together by a single instrumentality or movement, substantially as described.

5. The combination, with the bar B, of the sliding head E, having a yoke, E', at its lower 10 end to embrace gripping-jaws C C', hinged to a sleeve, C³, springs C⁴, for opening the gripping-jaws, and means for raising and lowering the sliding head and jaws, substantially as described.

6. In a cable-grip, the combination of the 15 hanger-bar B, sliding jaws C C', sliding head E, for raising, lowering, and closing said jaws, the pitman F, band-wheels G I, the gear-pinion upon the shaft of the wheel I, band H, and a segment-rack and hand-lever, L, substantially as and for the purpose described. 20
